Primary Examiner—Caron D. Veynar*Assistant Examiner*—Abraham Bahta(74) *Attorney, Agent, or Firm*—William W. Cochran;
Cochran Freund & Young LLC(57) **CLAIM**

The ornamental design for a speaker stand, as shown and described.

DESCRIPTION

FIG. 1 is an isometric view of a speaker stand showing my new design.

FIG. 2 is a front view thereof.

FIG. 3 is a top view thereof.

FIG. 4 is a right side view thereof.

FIG. 5 is a left side view thereof.

FIG. 6 is a rear view thereof; and,

FIG. 7 is a bottom view thereof.
